(57) CLAIM

The ornamental design for a combined cloth weight and cup holder, as shown and described.

DESCRIPTION

FIG. 1 is a front elevational perspective view of the combined cloth weight and cup holder shown in place holding a beverage can with napkin and fork;

FIG. 2 is a rear elevational view of the combined cloth weight and cup holder;

FIG. 3 is a front elevational view of the combined cloth weight and cup holder;

FIG. 4 is a front perspective view of the combined cloth weight and cup holder;

FIG. 5 is a bottom view of the combined cloth weight and cup holder; and,

FIG. 6 is a top view of the combined cloth weight and cup holder.

The broken line showing of a table cloth, napkin, beverage can, and fork, in FIG. 1, is for illustrative purposes only and forms no part of the claimed design.
